UNITED STATES PATENT OFFICE.

ROBERT W. HUNT, OF TROY, NEW YORK.

FEEDING-TABLE FOR ROLLING-MILLS.

SPECIFICATION forming part of Letters Patent No. 310,893, dated January 20, 1885.

Application filed May 8, 1884. (No model.)

To all whom it may concern:

Be it known that I, ROBERT W. HUNT, of the city of Troy, county of Rensselaer, State of New York, have invented a new and useful Improvement in Automatic Feed Mechanism for Rolling-Mills, of which the following is a specification.

My invention relates to mechanical attachments to rolling-mills for receiving, guiding, and automatically returning to the rolls a bar or rail-bloom being shaped by the latter, my improvements relating in the main to a mechanism that is used on one side of the train only, and which has stationary tables or platforms, as distinguished from apparatus having tables and combined rollers that are adapted to be alternately raised or depressed, so as to come opposite the upper and lower passes of the train, the object and purpose of my invention being to substitute machinery for hand-labor, and thus reduce the cost of production as respects the latter.

Accompanying this specification, to form a part of it, there are two plates of drawings containing four figures illustrating my invention, with the same designation of its parts by letter-reference used in all of them. Of these illustrations, Figure 1 shows a side elevation of a three-high-train mill, and an elevation of the mechanism containing my invention. Fig. 2 shows an end elevation of the mill and its housings shown at Fig. 1, and a side elevation of the mechanism containing my invention as connected therewith. Fig. 3 illustrates a top view of the mill and its housings, and a plan view of the mechanism containing my invention. Fig. 4 illustrates details of Fig. 2.

The several parts of a three-high-train rolling-mill and those of the mechanism containing my invention connected therewith are designated by letter-reference, and the function of the parts is explained as follows:

The letter H indicates the housings of the mill in which the bearings of the roller-shafts are placed; C', the coupler-shafts; D', spiral gears; S', the driving-shaft from which, as shown, power is derived to operate the train, the first series of the rolls indicated at A being the roughing-rolls, Y the second series, and those indicated F being the finishing-rolls, the rolls proper of each series being

indicated at R, all the foregoing parts constituting the usual factors of a three-high-train rolling-mill.

The letter I indicates an inclined platform or slideway, made with the friction-rollers m in its upper edge where opposite the last upper pass of the roughing-rolls, said pass being designated at P⁴. This inclined platform is arranged to receive the rail bloom or bar coming from the said upper pass of the roughing-rolls, so as to have it run out on the friction-rollers m, and from thence to slide downwardly until arrested by the upwardly-projected stop T, so as to be deposited on the roller R² of the shaft S². This latter shaft has its bearings in standards O², and it receives power from a connection made with the driving-shaft S' at M. When the rail bloom or bar coming from off the slideway I is thus deposited on the roller R², it is guided by the millman, and is conveyed by said roller to return through the shaping-rolls of the train by the lower pass, P⁴, of the middle train.

The letter S³ designates a horizontal shaft having its bearings in studs d³ d³, and constructed with a sprocket gear-wheel, G', at one of its ends outside of its bearing, and which by means of a chain belt, K, connects with another sprocket gear-wheel, G², on the shaft S², and the letter R³ indicates a conveying-roller arranged on said shaft S³. When the said shaft S³ is actuated by this connection made with a chain belt, the roller R³, located on it, rotates with its uppermost surface turning toward the train in the same manner as does the roller R² on the shaft S². This roller R³ is constructed with a grooved collar-guide, g', which is opposite to the upper pass, P⁴, of the middle train, and the roller R² on the shaft S² is constructed with a grooved collar-guide, g², which is opposite the lower pass, P⁶, of the same train. The letter h indicates an inclined guide-plate.

When the rail-bloom is entered through the upper pass, P⁴, of the middle train, to come frontward, it descends onto the grooved collar-guide g' of the roller R³ and the roller R², being guided thither by the guide h, and moving thereon against the rotation of the said rollers from the expelling force of the shaping-rolls of the train by which it is being ejected. Just at the time of leaving the shaping-rolls

of the train, the front end of the rail engages with a vertically-placed guide-plate, p , which deflects its outward end horizontally toward the inclined platform I, and thus causes its end that is nearest to the train to swing over into the grooved collar-guide g^2 of the roller R^2 , by which the rail-bloom is directed and returned to the train at and through the lower pass, P^6 , of said middle train. This combination of an inclined slideway, I, with the rollers $R^2 R^3$, the stop T, and plate p , as combined with a series of rolls making a part of a train, constitutes a separate part of my invention.

15 The inclined slideway I, considered by itself independently of the friction-rollers, which I have added thereto as an improvement, is an old device, and a part of my invention only when combined with the rollers $R^2 R^3$, stop T, 20 and guide p , with both of said rollers operated with a parallel rotation, which on its upper circumference is toward the train.

While I prefer to use the grooved collar-guides $g^1 g^2$, if desired, however, the said rollers 25 $R^2 R^3$ may be combined with the inclined slideway I, and used without said collar-guides on the rollers through the co-operation of the plate p and stop T, projected above said rollers, or the said plate and stop and an additional 30 plate upwardly projected from the floor oppositely to where the collar-guide g^2 is located on the roller R^2 . In either way of thus using the combined slideway the rollers $R^2 R^3$, in combination with the plate p and stop T, perform the same office for receiving, guiding, 35 and conveying the rail in return to the train. The function of the guide-plate p being to force the outwardly-approaching end of the rail toward the incline I, and thus actuate the other end to swing in so as to be opposite the lower pass, P^6 , of the middle series of the 40 train-rolls, any device performing the same relative function in an equivalent manner may be used in its stead.

45 The letters B' indicate a series of inclined platforms that at their ends where nearest the train are lower than at their outer ends.

The letters E indicate a series of horizontally-arranged rollers that are located parallel 50 to each other and to the train, with one of the inclined platforms placed between each two of said rollers. The shafts of these rollers E (with the exception of that indicated at E' , which is on the shaft S^2), have their bearings 55 in standards e . Sprocket-gears O on the shafts of said rollers E, and chain belts c , connect them to receive and communicate from one to the others parallel rotation, and with the upper part of said rotation directed toward the 60 train, motive power being communicated to this series of rollers E from the shaft S^2 by means of the sprocket-wheel O and the chain belt c .

The letters $d' d^2$ indicate two guide-collars 65 upon the roller E of the series, and D^2 a guide-plate arranged on that one of the platforms B' that is nearest to the train.

The letters L L indicate two guide-plates arranged on one of the platforms B' , and d^3 a collar arranged on one of the rollers E between 70 the ends of said plates.

The letter d^4 indicates another collar arranged on one of the rollers E oppositely to the collar d^2 on the roller E'.

The letters D^3 and D^4 designate plates on 75 the sides of two of the platforms B' , and D^6 a deflecting-plate on the end platform, B^2 , that is most remote from the train, all the platforms and the guide-plates thereon, as well as the series of rollers E being shown as opposite to the finishing-rolls of the train.

The operation of the inclined platforms B' , the guide-plates arranged thereon, the rollers E, and the collars on said rollers, is as follows: The end of the rail-bloom coming 80 from the upper pass, P^7 , of the finishing-rolls descends upon one of the said platforms to run up thereon, being deflected in emerging from the shaping-rolls of the train by the inclined guide l' , and in descending upon the 85 platforms it runs out over the latter and on the rollers E against the rotation of said rollers from the expelling force imparted to the rail-bloom by the shaping-rolls from which it emerges. The rail-bloom thus coming from 90 said last-named upper pass of the finishing series of rails as guided by the incline l' and standard K^2 , is directed outwardly and onwardly between the plates L L, so as to run upon its side from the engagement of the 95 grooved side of the rail-bloom with the collars d' and d^2 , the length of the rail-bloom at this stage of its production not reaching to the platforms at the outer end of the series. After the rail-bloom has thus run 100 through and left the upper pass, P^7 , of the finishing-rolls, so as to be over the platforms B' and the rollers E, the forward progressive movement having carried it from off the collar d' , as the rollers E commence to move 105 the rail toward the train, it is still held upon its side by the action of the plates L L, and the collar d^3 , while being returned to the lower pass, P^8 , of the finishing-rolls being 110 guided therein by the incline i at the side of 115 said pass. When the rail is returned forward through the upper pass, P^9 , of the finishing-rolls, as it emerges therefrom it is guided in its descent to the platforms B' and rollers E by the inclined guide l^2 , the latter 120 causing it as it comes from the train-rolls on its side, in connection with the engagement of its outer end with the deflecting-plate D^6 , to be deposited on the collars $d' d^4$, the head 125 of the rail being on the collars with the edge of its flange resting on the rollers E. When the rail has left the train-rolls, and on coming under the motor influence of the rotating collars and rollers E, on which it rests, it is moved in return toward the train, and by the 130 action of the said collars and guide-plate D^6 it is directed so as to enter the last pass of the train, which completes the operation.

The letter N designates a stop, which may

be moved in front of the lower passes of the finishing-train to stop the passage of the rail when it become necessary to cut from it a feather or irregularity that may have been developed thereon.

5 The letter N^2 designates a pivoted lever attached to said stop, having its fulcrum at n , and by which lever the said stop is operated.

10 The letter N^3 designates a like stop arranged opposite the middle train, that is provided with a pivoted lever, b' , having its fulcrum at b^2 , which lever is used for the same purpose as the other stop at an earlier period of the manipulation.

15 The sprocket-gears used on all of the roller-shafts are of the form and kind illustrated in the annex figure X of Fig. 2, wherein they are shown in a comparatively-enlarged representation, these elements where illustrated in 20 the other figures being from necessity too small, when drawn in correct proportion to the other parts, to be represented with definiteness. The connection at M , by which power is applied to the shaft S^2 from the shaft S' of the 25 train, is made by the spur W' on the shaft S' , the gear-wheel W^2 on the counter-shaft S' , and the gear-wheel W^4 on the latter, which engages with the gear-wheel W^5 on the shaft S^2 . If desired, the feed mechanism may be operated

30 by power other than that derived from the train. As the function of the inclined platforms B' , rollers E , and combined collars and guide-plates which I show and describe is to receive the rail-bloom from the upper passes 35 of the finishing-rolls in their sequence, and to return it to and through the lower passes of said rolls in their order, and these functions would be the same whether there were combined with said platforms B' and rollers E the

40 same arrangement of collars and guide-plates which I show, or some equivalent arrangement of means were used in the same connection and combination that would operate in substantially the same manner, hence I do 45 not limit my invention as relates thereto to the precise form and arrangement of collars and guide-plates which I combine with the said rollers and platforms.

50 It will be understood that my invention relates to an attachment that is arranged upon one side of a rail-train or rolling-mill train, and for operating the rail-bloom on the opposite side thereof, hand-labor or any of the well-known mechanisms that are suitable for 55 such use may be employed.

The function of the chain belts and sprocket-gears being to actuate the rollers E to turn with a parallel axial rotation, and with their tops where arranged to be in contact with the 60 rail turning toward the train, any system of belts and pulleys or gears that will produce this same parallel rotation of said rollers may be used, instead of sprocket-gears and chains, if desired.

65 The letters V indicate a series of friction-rollers that are arranged in front of and parallel to the rollers E , and having arranged be-

tween each two of them, and that one of the rollers E to which they are adjacent, inclined platforms B^2 , like those between the said rollers E . These friction-rollers move with the reciprocating passage of the rail as it rides over them at its outer end when coming from the roll-train, and when returning for the final pass through the latter.

70 The guide-plates D^3 D^4 may be dispensed with, as their use is merely to guard against contingencies, and the number of the rollers E may be increased or diminished, and so may be the number of the friction-rollers V , and 75 their intermediate platforms, B^2 .

75 The mechanism thus illustrated and described for receiving, guiding, and returning the rails to the train operates automatically when power is applied thereto. It does its 80 work uniformly, and dispenses with the services of several skilled men; and while I have in the main described it as more particularly adapted for rails, it may be employed for the 85 rolling of any form of iron requiring a like 90 manipulation.

Having thus described my invention, what I claim, and desire to secure by Letters Patent, is—

1. In an automatic feed attachment to a rolling-mill, the combination of the inclined platform or slideway I , arranged with reference to the roughing-rolls, as shown, the conveying-rollers R^2 and R^3 , constructed to turn with parallel rotation, and with the upper 95 part of said rotation directed toward the train, the guide h , stop T , and the guide-plate p , with the said parts constructed and arranged to operate substantially in the manner, as and for the purposes set forth.

100 2. In an automatic feed attachment to a rolling-mill, the combination of the inclined platform or slideway I , arranged with reference to the roughing-rolls, as shown, the conveying-roller R^2 , made with the grooved collar g^2 , 110 the roller R^3 , made with the grooved collar g^3 , the guide h , the stop T , and the upwardly-projected guide-plate p , with the said parts constructed and arranged to operate substantially in the manner as and for the purposes set forth.

115 3. In an automatic feed attachment to a rolling-mill, the combination of the inclined platforms B' , the roller E , the collars d^1 d^2 , and the guide-plates L L , said parts being constructed and arranged to operate substantially in the 120 manner as and for the purposes set forth.

4. In an automatic feed attachment to a rolling-mill, the combination of the inclined platforms B' , the rollers E , and the guides l and l' , with the said parts constructed and arranged 125 to operate substantially as and for the purposes set forth.

5. In an automatic feed attachment to a rolling-mill, the combination of the inclined platforms B' , the rollers E , the collars d^1 d^2 d^3 d^4 , 130 the guides l l' , with the said parts constructed and arranged to operate substantially in the manner as and for the purposes set forth.

6. In an automatic feed attachment to a roll-

ing-mill, the combination of the inclined platforms B', the rollers E, the collars d' d² d³ d⁴, the guides L L, with the said parts constructed and arranged to operate substantially in the 5 manner as and for the purposes set forth.

7. In an automatic feed attachment to a rolling-mill, the combination of the inclined platforms B', the rollers E, collars d' d² d³ d⁴, guides l' l², plates L L, and guide-plate D², with said 10 parts constructed and arranged to operate substantially in the manner as and for the purposes set forth.

8. In an automatic feed attachment to a rolling-mill, the combination of the rollers E, actuated to turn with a parallel rotation, that in its 15 upper circumference is toward the train, the inclined platforms B', the friction-rollers V, the inclined platforms B², and deflecting-plate D⁶, with said parts arranged with reference to 20 each other, and constructed to be operated sub-

stantially in the manner as and for the purposes set forth.

9. In combination with an automatic feed mechanism for a rolling-mill, the stop N, arranged in front of the lower pass-openings of 25 the train-rolls, and constructed to operate substantially in the manner as and for the purposes set forth.

10. In an inclined platform or slideway for a rolling-mill train, the friction-rollers m, arranged in the upper edge of the said platform, as and for the purposes set forth.

Signed at Troy, New York, this 26th day of April, 1884, and in the presence of the two witnesses whose names were by them hereto 30 written.

ROBERT W. HUNT.
